US0D1080616S

(12) United States Design Patent (10) Patent No.: US D1,080,616 S
(45) Date of Patent: * Jun. 24, 2025

(54) CASE FOR WATCH

(71) Applicant: CITIZEN WATCH CO., LTD.,
Nishitokyo (JP)

(72) Inventor: Souta Okumura, Nishitokyo (JP)

(73) Assignee: CITIZEN WATCH CO., LTD., Tokyo
(JP)

() Term: 15 Years

(21) Appl. No.: 29/890,410

(22) Filed: Apr. 24, 2023

(51) LOC (15) Cl. 10-02

(57) CLAIM

The ornamental design for a case for watch, as shown and described.

DESCRIPTION

FIG. 1 is a front perspective view of a case for watch showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a rear perspective view thereof.

The broken lines depict portions of the case for watch that form no part of the claimed design.

1 Claim, 6 Drawing Sheets
